SHUTTLE FEELER THREAD PARTER AND CLAMP

Filed March 30, 1927

INVENTOR:
Harry A. Davis
BY Robert A. Haine
ATTORNEY

UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

SHUTTLE-FEELER THREAD PARTER AND CLAMP.

Application filed March 30, 1927. Serial No. 179,640.

This invention relates to shuttle feeler thread parters and clamps whereby the outgoing filling end is parted near the inner end of the shuttle and that portion leading to the cloth selvage is clamped and moved frontwardly for the action of the temple thread cutter.

Replenishing looms are now ordinarily provided with some means for parting and clamping the outgoing filling end and carrying it frontwardly to position the part leading to the cloth selvage for the action of the temple thread cutter, and as pointed out in the patent to Harry A. Davis, No. 1,591,289, dated July 6, 1926, the clamped end of the filling is liable to be drawn from the clamp on the frontward movement of the shuttle feeler. In the patent mentioned, the fixed and the movable parting member and the fixed clamping member were associated to part and clamp the outgoing filling end, and in order to insure that the end of the filling should be properly clamped and held, the movable parting member was provided with a thread clamping portion extending downwardly beyond the cutting edge of the movable parter and preferably acting to clamp the thread prior to the parting operation. This construction has been found in practice to be effective and satisfactory and when the movable combined parter and clamp was opened, the scored face, constituting the clamp of the parting member, served to lift the thread.

It is desirable at times to have ready access to the cutting edge of the parting member for sharpening or other purposes, and the present invention, therefore, is a further development of the shuttle feeler thread parter and clamp shown, described and claimed in the Davis patent.

One of the objects of the present invention is to provide a thread parter and clamp of the general character of that described in the Davis patent, wherein ready access may be had to the cutting edge of the parting member to sharpen or repair the same. An important feature of the present invention, therefore, consists in a shuttle feeler thread parter and clamp wherein the clamping member is separate from the parting member and so connected thereto that the two members may be relatively moved to per-

mit ready access to the cutting edge of the parting member.

The invention and novel features thereof will best be made clear from the following description and the accompanying drawings of one good form thereof.

In the drawings:

Fig. 1 is a perspective view of a shuttle feeler thread parter and clamp containing the present invention;

Fig. 2 is a side elevation of the parting and clamping members relatively moved from their cooperating relation in parting and clamping the thread, to permit ready access to the sharpening edge of the parting member;

Fig. 3 is a view showing the parting and clamping features of the present invention in separated relation; and

Fig. 4 is a plan view of the assembled thread parter and clamp.

The shuttle feeler 1 may be of any usual construction and preferably is provided with the recessed jaws 2 and 3 for engagement with the shuttle should it not be properly boxed, and also for positioning the outgoing filling end for the action of the thread parter and clamp.

As is usual in looms having a shuttle feeler to ascertain whether the shuttle is properly boxed, the shuttle feeler is normally in front position and on call for replenishment of filling is moved rearwardly, but the means for thus controlling the shuttle feeler is not here shown and described because the details thereof form no part of the present invention and are now well understood in the art. The shuttle feeler, in accordance with the present invention, has mounted thereon the thread parter and clamp, and, as shown in the present instance of the invention, there is mounted on the shuttle feeler a fixed thread parting member 4 and a fixed thread clamping member 5, between which is pivotally mounted the movable thread parter and clamp.

In the Davis patent, herefore mentioned, the movable thread parter and clamp was constituted by a parting member having rigidly associated therewith the clamping member which extended below the cutting edge of the parter. In accordance with the present invention, however, the movable

parting member and the associated clamping member are formed separately and connected together in such manner that the two may be relatively moved when it is desired to have access to the cutting edge of the parter.

As shown in the present instance of the invention, the shuttle feeler 1 has extending laterally therefrom the bolt or pivotal support 6 which extends laterally through the members constituting the thread parter and clamp, and interposed between the head of the bolt 6 and the fixed clamping member 5 is a spring washer 7 normally acting in a lateral direction to hold the elements of the thread parter and clamp in associated relation.

As indicated more clearly in Fig. 3, the fixed thread parting member 4 has an opening 8 through which the bolt 6 extends and is held in fixed position by means of a pin 9 engaging the bifurcated end portion 10 of the fixed parting member. Similarly, the fixed clamping member 5 is provided with an opening 11 through which the bolt or pivotal support 6 passes, and the bifurcated end 12 of the clamping member also engages the bolt 9, the construction being such that the fixed parting member 4 and the fixed clamping member 5 are held in fixed position on the shuttle feeler.

Interposed between the fixed clamping member 5 and the fixed parting member 4, and mounted for pivotal movement upon the bolt or pivotal support 6 are the movable parting member 13 and the separate or independent movable clamping member 14, each of which has a forwardly extending tail portion 15 and 16.

The parting member 13 and the clamping member 14 are pivotally connected at 17, Fig. 2, and the forwardly extending tail portions 15 and 16 of the two members are detachably locked together by a bolt or pin 18 in order to cause movement of the parting and clamping members 13 and 14 as a unit in parting and clamping the thread. In order that the parting member 13 and the separate clamping member 14 when thus connected for movement as a unit may have pivotal motion about the pin or pivotal support 6, each is provided with an opening 19 through which the pin 9, which holds the fixed parting member and the fixed clamping member in their fixed position, passes.

When the movable parting member 13 and the movable clamping member 14 are associated and locked together for clamping and parting the thread, the clamping portion 20 of the clamping member preferably extends downwardly beyond the cutting edge 21 of the parting member, with the result that upon pivotal movement of the interlocked parting and clamping members, the thread 65 will be first clamped and then parted, so

that the end leading to the cloth selvage may be properly carried forward on the forward movement of the shuttle feeler to position that end for the action of the temple thread cutter. In the present instance of the invention, the clamping face of the clamping member 14 is preferably scored or grooved, as at 22, and since the clamping surface of the clamping member precedes the cutting edge of the parting member during their joint movement to part and clamp the thread, the latter will be first clamped between the movable clamping member 14 and the fixed clamping member 5, and thereafter, the cutting edge 21 of the parting member will come into action to part the thread.

Extending laterally from the tail portion of the movable clamping member is a pin 23, which on rearward movement of the shuttle feeler is actuated by an opening device, now well understood in the art, to cause the movable thread parter and clamp to open, as indicated in Fig. 1. The parts being in the position shown in Fig. 1 and the shuttle feeler being in rearward position, the movable thread parter and clamp are actuated, preferably by forward movement of the lay, to cause the two to move as a unit, first to clamp, and then part the thread, and on forward movement of the shuttle feeler to carry the clamped thread forwardly in position for the operation of the temple thread cutter.

As indicated in Fig. 1, the clamping portion of the movable clamping member 14 extends below the cutting edge 21 of the parting member 13, and to permit ready access to the cutting edge of the parting member, the present invention contemplates that the movable parting member 13 and the movable clamping member 14 may be relatively moved upon release of the lock 18 which normally acts to unite the movable parting and clamping members for their joint operation in parting and clamping the thread, as indicated in Fig. 2.

When access is desired to the cutting edge of the parting member 13, the bolt or pivotal support 6 is removed, together with the washer 7 and fixed clamping member 5, as indicated in Fig. 3, whereupon the movable parting member 13 and its associated separate clamping member 14 may be removed and upon disengagement of the lock 18 from the forwardly extending tail portion of the said members, they may be relatively moved, as indicated in Fig. 2, to permit access to the cutting edge of the movable parting member.

During normal weaving operation, the movable parting member 13 and separate clamping member 14 are locked together by the lock or bolt 18 for movement as a unit in clamping and parting the thread, and

when ready access is desired to the parting edge 21 of the parting member 13, the bolt 6, washer 7 and clamping member 5 are removed, thus freeing the parting and clamping members 13 and 14 for relative movement substantially in the position indicated in Fig. 2, whereby the parting edge 21 of the parting member may be sharpened or otherwise repaired.

10 What is claimed is:

1. In a shuttle feeler thread parter and clamp, the combination of the shuttle feeler having fixed parting and clamping members, a movable thread parter between said members, 15 a clamping member, pivotal connections between the parting and clamping members, a locking element connecting the two members, said pivotal connection and locking element being removable from the shuttle feeler with the said members while locked and permitting the movable parting and clamping members to be relatively turned upon their pivotal connections when removed from the shuttle feeler and unlocked that ready 20 access may be had to the parting edge of the movable parting member.

2. In a shuttle feeler thread parter and clamp, the combination of a shuttle feeler, a relatively movable parting member to part the thread, a clamping member pivotally connected to the movable parting member, a locking element for locking said members from relative pivotal movement both when said members are connected to and detached from the shuttle feeler and permitting said members to be unlocked when removed from the shuttle feeler that ready access may be had to the parting edge of the parting member.

3. In a shuttle feeler thread parter and clamp, the combination of a shuttle feeler, a thread parter including a movable parting member, a thread clamp including a movable clamping member separate from the 40 parting member, a pivotal connection be-

tween said members, a pivot connecting both of said members to the shuttle feeler, a locking element for locking the two members from relative pivotal movement and removable from the shuttle feeler with the two members that the two members may be relatively turned when removed from the shuttle feeler and then unlocked.

4. In a shuttle feeler thread parter and clamp, the combination of a shuttle feeler, a 55 thread parter including a movable parting member having a cutting edge, a thread clamp including a movable clamping member, a pivot connecting both of said members to the shuttle feeler, a separate pivotal connection between the parting and clamping members, a lock for locking said members from relative pivotal movement about their pivot connection with the shuttle feeler that the two members may be removed from their connection with the shuttle feeler while pivoted together and locked and thereafter unlocked to permit access to the cutting edge 60 of the parting member.

5. In a shuttle feeler thread parter and clamp, the combination of a shuttle feeler, a thread parter including a movable parting member having a cutting edge and a frontwardly extending tail portion, a thread 75 clamping member separate from the parting member and having a frontwardly extending tail portion, a pivotal connection between said members and the shuttle feeler, a separate pivot connecting the tail portions of said members, a lock for securing the tail 80 portions together that the two members while pivoted together and locked from relative movement may be removed from the shuttle feeler and by release of the lock may be turned on the pivot connecting them to 85 permit sharpening the cutting edge of the movable parting member.

In testimony whereof, I have signed my name to this specification.

HARRY A. DAVIS.
